STACKING MACHINE

Hermann Hill, Bridgeport, Conn., assignor to
 Magazine Repeating Razor Company, New
 York, N. Y., a corporation of New Jersey

Application November 10, 1941, Serial No. 418,607

10 Claims. (Cl. 214—7)

The invention relates to machines for stacking articles, more particularly articles that are thin, as, for example, razor blades and the like.

The main object is a machine of that character capable of stacking the articles rapidly and accurately and without injury to them.

Another object is a stacking machine for especially thin articles, the stacking mechanism of which is capable of very fine and accurate adjustment.

While the machine is adaptable as above stated for stacking a great variety of articles, I will, for purposes of illustration, describe it as adapted to stack razor blades preparatory to packing them in cartons or other receptacles for dispensing them to the consumer.

Referring to the drawings:

Fig. 1 is a plan view of the machine;

Fig. 2 is a plan view showing the blade strip feeding and breaking mechanisms;

Fig. 3 is a side elevation corresponding to Fig. 2;

Fig. 4 is an end view corresponding to Fig. 3;

Fig. 5 is a side elevation showing the blade loading platform and accompanying mechanism;

Fig. 6 is a plan view of the blade loading platform;

Fig. 7 is an enlarged plan view of the blade stacking mechanism;

Fig. 8 is an end view corresponding to Fig. 7;

Fig. 9 is a view on the line 9—9 of Fig. 7;

Figs. 10a, 10b, and 10c are diagrammatic views showing the several steps in a cycle of the blade stacking mechanism;

Figs. 11 and 12 show the two slides separated from each other which operate directly to build the stack;

Fig. 13 is a perspective view of the entrant end of the tray.

The blade strip which the machine is adapted to separate into single blades and to stack them is shown at 10 in Fig. 3. Both its sharpened edge 11 and the unsharpened edge or heel 12 are provided with spaced pairs of notches, the spacing of each pair being equal to the length of the blade that is to be severed and stacked and the individuals of each pair being transversely opposite each other.

As to the machine itself, it can conveniently be described by dividing the description into four sub-headings—viz., the "strip feeding mechanism," the "breaking mechanism," the "blade stacking mechanism," and the "blade stacking platform."

The strip feeding mechanism, as also the

breaking mechanism and the blade stacking mechanism, are all operated through appropriate gearing from the shaft 13.

Strip feeding mechanism

Considering the strip feeding mechanism (best shown in Fig. 3), the shaft 13 is provided with an eccentric 14 on which is rotatably mounted the bearing 15 of the connecting rod 16. The opposite end of the connecting rod is provided with a bearing 17 rotatably mounted on an eccentric stub shaft 18 extending from socket 18a on the slide block 20. The slide block 20 is slidably mounted on the guide 21 and is therefore capable of a reciprocating motion equal to twice the radius of eccentricity of the eccentric 14. The guide 21 is fixedly mounted to the frame 22 which supports the operating parts.

The stub shaft 18 is secured in a socket 23 fixedly mounted on the slide block. By loosening the set screw 19 the stub shaft may be rotated in either direction and thus effect a shifting of the stroke of the slide block, the length of the stroke however remaining unchanged. Also there is mounted on the slide block a bell crank lever 24 mounted to rock on the stub shaft 25. One arm 26 of the bell crank lever is provided with a stop 27 in the form of a screw for micrometer adjustment and a lock nut 28 for locking the screw in any set position.

The other arm 30 of the bell crank lever is provided with a small stub shaft 31 on which is rockably mounted a pawl 32 spring-pressed by the spring 32a in a clockwise direction. The spring is stiff enough to cause feeding of the strip, but weak enough to yield if an obstruction to the feed is met. An adjusting screw 33 threaded into the block 34 limits the amount of rotation of which the pawl is capable under the influence of the spring, and the screw may be adjusted to any position within the range of its effective length. The tension spring 35 connects the arm 26 of the bell crank lever with a pin 36 in the slide block 20 and draws the stop 27 yieldingly into abutment with the socket 23. The stroke of the slide block is adjusted to the spacing of the notches in the heel of the blade strip. The blade strip, as shown, is feeding in the direction of the arrow "A" (Fig. 3). As the slide block is retracted when the eccentric 14 rotates to its rearward position—i. e., to the left as shown in Fig. 3, the spring 35 flexes and the pawl 32 trails along the heel of the blade strip, and due to the spacing of the notches,

55

enters a notch at the end of its rearward stroke or it may overrun a notch slightly and pick it up on the feeding stroke. As the motion of the slide block is reversed, the pawl, having entered a notch, advances the strip the length of a single blade.

Since the action of the pawl would lift or tend to lift the blade strip were the latter not confined, there is provided a pair of rollers 40 and 41, each having a peripheral groove 42 of insufficient width to permit a blade to enter therein beyond its extreme cutting edge. The cutting edge of the strip is therefore not injured as it passes beneath the idler rollers and through the grooves in their peripheries. The idler rollers are mounted on a block 43 erected on the frame of the machine.

In order to prevent the blade strip from being retracted by the friction of the pawl 32 during the retractive movement of the slide block, a check pawl 46 rotatably mounted on the pin 46a projecting from the frame is provided. A spring 46b connecting the pawl with the block 46c tends to cause the pawl to rotate in a clockwise direction. As the blade strip travels in its feeding direction, this pawl trails along it exerting only as much pressure thereon as the spring is capable of exerting, which need be very little. However, any retrograde movement of the blade strip that might be caused by the rearward drag of the pawl 32 immediately causes a checking or snubbing action to take place.

Braking mechanism

The purpose of this mechanism is to break the blades from the strip one by one as successive pairs of notches reach a designated position. This is done by means of the hammer head 60 (Figs. 2 and 3) bolted as shown to the arm 61 of a lever pivoted at 62 to the frame of the machine. The short arm 63 of the lever carries a cam following roller 64, which follows the periphery of the cam 65 as the latter fixedly mounted on the main shaft 13 rotates. In the cam profile there is a rather abrupt inturn toward the shaft 13, as shown at 66, and as the cam rotates anti-clockwise as indicated by the arrow "B" (Fig. 2), the cam following roller 64 is thrown suddenly toward the shaft 13 by the expansion of the spring 67, surrounding the rod 67a and interposed between the head 67b and the stop 67c. The rod is hingedly connected to the hammer lever at 68. The hammer therefore delivers a sharp blow against the blade strip, the notches of which are in line with the slit 68 in the anvil 70 and the blunt edge 71 of the hammer, it being understood that the feed is so timed as to cause the strip to dwell in the position just mentioned as the blow is struck. The blade strip being of hardened steel is therefore severed, or perhaps more correctly speaking fractured, on a transverse line through opposing notches of a pair. The stroke of the hammer is so timed with respect to the stroke of the slide block 20 that the blow takes place during the retractive movement of the slide block. After the blow has been delivered, the hammer is retracted by virtue of the gradually increasing radius of the cam 65, as shown in Fig. 2, until it reaches the high point 65a whereupon another blow follows and so on as the step-by-step feed continues.

Blade stacking mechanism

The general relationship of the blade stacking mechanism to the remaining units is shown in

Fig. 1. The mechanism itself is shown in detail in Figs. 7-12, both inclusive. Its object is to stack the blades that have been severed from the blade strip by the hammer as will be later described. As successive blades are severed by the hammer, they travel in tandem, impelled by the feeding mechanism, in a groove 80 in the guide 81. As the severed blades successively reach the stacking mechanism, the stack is, during the retractive movement of the feed slide 20, forced upwardly at each stroke against gravity and friction a distance equal to the thickness of a blade. This is accomplished by means of two slides indicated generally by the letters "K" and "L" (Fig. 12) and the necessary operating and adjusting mechanism. The slide "K" comprises two rails 82 and 83 connected together by a plate 84, there being fixedly mounted on the rails two blocks 86 and 87 which bridge them. Also there is fixedly attached to the plate 84 a depending block 90. It may be considered as two slides rigidly connected together. The slide "L" comprises a narrow plate of a width to slidably fit between the rails of the slide "K," and it is provided with a fixedly attached depending block 91.

The depending block 90 is smooth-bored at 92 to accommodate a plunger 93 and is counterbored to accommodate the extension spring 94, the head 95 of the plunger bearing against the spring. Adjustment of the plunger is desirable in order to vary its stroke as will appear, and for this purpose the nut 96 is provided into which the plunger is threaded. The nut is prevented from turning as the plunger is adjusted, by the stud 97, which enters the groove 100. The plunger is set to any given position by the set screw 101, which enters the annular groove 102 in the plunger. As will presently appear, the adjustment is made use of to vary the width of the gap 95a.

In the block 87, which forms a part of the slide "K," as has been described, is threaded a screw 105, which by abutting against the block 106 establishes a limit to the movement of the slide "K" in a right-hand direction as shown in Fig. 9. This limit can be varied by adjusting the screw, which is set to a fixed position by the set screw 107.

The stroke of the slide "K" is limited in a left-hand direction (Fig. 9) by the screw 111 threaded into the stop block 110 affixed to the frame. This limit may obviously be varied by operating the screw which opposes the block 86 on the slide "K."

The slide "L," as has been noted, operates between the rails 82 and 83 of the slide "K." The block 81 is provided with a threaded bore which accommodates the screw 112, which is fixed in any set position by the set screw 113. By turning this screw one way or the other, the width of the gap 103 may be varied. A limit to the right-hand movement of the slide "L" is established by the screw 114, which enters the block 91. The screw has a loose fit in the frame portion 115 and is provided with a stop nut 116 and a lock nut 117.

The slide "K" is spring-pressed forwardly (as shown in Fig. 7) by the lever 120 pivoted on the stud 121 projecting from the frame 122. The contractile spring 123 exerts a pull on the long arm of the lever causing the end of the short arm to bear against the abutment 124 of the slide. The slide "L" is similarly actuated by the lever 125 and the contractile spring 126, the short arm

of the lever bearing against the abutment 126a.

The slides are operated from the main shaft 13 through the cam 127, the cam follower 128, the lever 130 pivoted to the frame at 131, the connecting rod 132 pivoted to the lever at 133, and to a bell crank lever 134 at 135. The bell crank lever rocks on a stud 136 projecting from the main frame and is pivotally connected at 137 to a second connecting rod 138. This connecting rod is, in turn, pivotally connected at 140 to a lever 141 which rocks on a stud 142 projecting from the frame. The free arm 143 of this lever is provided with a stud 144. The track of the peripheral cam 127 has a high portion and a low portion, the high portion serving to operate the lever 141 to drive the plunger 93 to the left and the low portion serving to release the plunger and permit the levers 120 and 125 to operate the slides.

At this point the mode of operation of the blade stacking mechanism will be described, and to assist in the explanation reference is made to Figs. 10a, 10b, and 10c, showing a cycle of steps in adding a blade to the bottom of the stack "X."

The cycle may be assumed to begin when the parts are in the position shown in Fig. 10a—i. e., when both slides impelled by their actuating springs are in the extreme forward position—i. e., toward the upper part of the sheet as shown in Fig. 7. In this position the bottom blade of the stack, and consequently the entire stack, is resting against the working faces of the slides, the bottom blade itself being offset from the line of travel of the feed a distance equal to a blade thickness. Next, the slide "K" is retracted to clear the line of feed and the incoming blade 145 is thrust by the feeding mechanism behind the bottom blade of the stack until it is about half-way across the slide "L," whereupon the slide "L" is retracted and the blade 145 continues until the feeding stroke is completed. The slide "K" is beveled off at 106a and 106b and the slide "L" is beveled off at 106c to allow unimpeded travel of the incoming blade. This completes a cycle, and of course it is repeated as each successive blade is added to the stack.

Having described the cycle of steps carried out by the stacking mechanism, the way in which it is carried out will now be described:

Referring to Fig. 9, a stud 144 has a fixed stroke, fixed not only as to length but as to position of its extremities. Forward motion of the slide "K" is limited to a desired position by adjusting the screw 105 so that it bears against the block 106 when the slide "K" is in the position shown in Fig. 10a. Rearward motion of the slide "K" is limited by the adjusting screw 111, which is adjusted to stop this rearward motion when the slide "K" is in the position shown in Fig. 10b.

Forward motion of the slide "L" is limited by the stop nut 116 on the screw 115, which is threaded into the block 91. Rearward motion of the slide "L" is limited by the position of the screw 112, also threaded in the block 91 and set to a fixed position by the set screw 113. When the working stroke of the lever 141 takes place, the stud 144 contacts with the head 95 of the plunger 93. The spring 94 is considerably stiffer than the springs 123 and 126 and is preferably preloaded, and therefore the slide "L" is driven rearwardly against the relatively weak opposition of the springs 123 and 126. When the block 86 contacts with the adjusting screw 111, rearward motion of the slide "K" ceases, but since there is a positive stop to this rearward motion, the spring 94 is now compressed, and then the slide

"L" is in turn carried back to the position shown in Fig. 10c, its limit of rearward motion being fixed as above stated by properly positioning the adjusting screw 112. Adjustment of the plunger 93, in order that it may have a proper relationship to the stroke of the lever 141 is effected by turning it one way or the other as required in the nut 96, which is non-rotatable by virtue of the stud 97 entering the groove 100. The plunger may be set by means of the set screw 101.

It will be apparent that provision has been fully made for fixing not only the length of stroke of both slides but also the forward and rearward limits for any given length of stroke. Since the absolute length of the stroke is in any case very small, being not more than the thickness of a blade which may not be in excess of .010", it will be apparent that this very fine adjustment is necessary.

Blade stacking platform

As each blade is moved laterally by the blade stacking mechanism, it passes into an inclined trough 150 driving ahead of it any blades which have previously been stacked. Thence it passes along with the preceding and succeeding blades into the tray 151. The tray has side walls 152 and 153 for confining the stack, and the stack as a whole moves along skids 154, 154. The tray is provided with a gate 155 which is hinged on the rod 156, which in turn is mounted in the bearings 157 and 158. A torsion spring 159 exerts a force that normally keeps the gate raised, so that, in order to permit blades to enter the tray, the gate may be raised by releasing it from the spring catch 159a. When the gate is lowered, the spring catch 159a snaps into the notch 159b of the gate and holds it closed. The lower edge of the gate may be sharp so that it may, in lowering, enter easily between adjacent blades of the stack. The tray rests on an inclined platform 160, and is located in a position laterally by means of two cradles 161 and 162 which are carried at the ends of arms 163 and 164. The cradles normally project above the surface of the platform but are capable of being pressed down until they are wholly below the surface of the platform. This is accomplished by rigidly mounting the arms on the shaft 165 which is supported in bearings 166 and 167. A torsion spring 170 is provided and this normally causes the cradles to project above the surface of the platform. They are, however, prevented from rising beyond a certain distance by the projections 170a and 170b which abut against the lower side of the platform.

It will be observed that the ends of the cradles slant downwardly toward the platform. The purpose of this will be presently explained.

In the ordinary use of the machine it is highly desirable that, when a tray has been fully loaded, it be removed as quickly as possible and a new one substituted therefor in order that it shall not be necessary to stop the machine. I therefore provide a mechanism which in co-operation with the cradles effects this purpose. It comprises two arms 180 and 181 beneath the stacking platform but terminating in hooks 182 and 183, which project upwardly above the surface of the stacking platform through slots 184 and 185 in the latter. They are supported by pins 186 and 187 which can ride along the platform. The arms are pivotally connected at 190 and 191 to arms 192 and 193, these latter arms in turn being non-rotatably mounted on the shaft 194.

The shaft 194 is supported by hangers 195 and 196 in which it may rotate. A handle 197 is non-rotatably mounted on the shaft 194. By rotating the handle clockwise as shown in Fig. 6, the hooks are drawn along the slots. An empty tray may be placed on the platform against the hooks. By rotating the shaft 194 clockwise (see Fig. 6), the empty tray is drawn laterally, forcing down the cradles and thus releasing the loaded tray until the empty tray is properly aligned with the trough, whereupon the cradles snap up and secure it in place. The loaded tray may then be removed. If desired, stops 200 and 201 may be provided to prevent overthrow of the loaded tray, and stop 202 may also be provided to resist any upward push as the tray is being filled.

Before the last described operation is carried out, the gate to the loaded tray is of course closed, the stack of blades being separated by a suitable tool to permit this to be done.

While I have described a certain particular construction in which my invention is incorporated, I do not desire to be limited to this particular embodiment since many changes and modifications may easily be made without departing from the spirit and scope of the invention as set forth in the following claims.

I claim:

1. In a machine for stacking razor blades and the like, a pair of independently movable slide units, stops adapted to limit the movement of each unit in both directions, spring means normally urging both the slide units to advance position, one of the units being provided with additional spring means more resistant to flexure than the spring means urging it to advance position, means acting intermittently on the said additional spring means to retract the said slide unit against the resistance of its advancing spring means and to effect engagement with the second slide unit and cause retractive movement thereof after the first-mentioned slide unit has been fully retracted, and means for feeding articles across the path of the slide units and in advance of their working faces.

2. In a machine for stacking razor blades and the like, a pair of independently movable slide units, one of the units comprising a pair of spaced connected slides and the second unit comprising a single slide positioned between the members of the pair, stops adapted to limit the movement of each unit in both directions, spring means normally urging both the units to advance position, the first-mentioned unit being provided with additional spring means more resistant to flexure than the spring means that urges it to advance position, means acting intermittently on said additional spring means to retract the said first-mentioned slide unit against the resistance of its advancing spring means and to effect engagement with the second slide unit and cause retractive movement thereof after the first-mentioned slide unit has been fully retracted, and means for feeding articles across the path of the slide units and in advance of their working faces, the said working faces being chamfered to permit the feeding of such articles without positive obstruction thereto.

3. In a machine for stacking razor blades and the like, a pair of independently movable slide units, one of the units comprising a pair of spaced connected slides and the second unit comprising a single slide positioned between the members of the pair, stops adapted to limit the movement of each unit in both directions, spring

means normally urging both the units to advance position, the first-mentioned unit being provided with additional spring means more resistant to flexure than the spring means that urges it to advance position, means acting intermittently on said additional spring means to retract the said first-mentioned slide unit against the resistance of its advancing spring means and to effect engagement with the second slide unit and cause retractive movement thereof after the first-mentioned slide unit has been fully retracted, and means for feeding articles across the path of the slide units and in advance of their working faces, the said working faces being chamfered to permit the feeding of such articles without positive obstruction thereto, the initial stage of the feed taking place as the first-mentioned slide is retracted and the said feed continuing into completion as the last-mentioned slide is retracted.

4. In a machine for stacking razor blades and the like, a pair of connected spaced parallel slides, a third slide positioned intermediate the members of the pair, separate spring means for the pair of slides and for the third slide respectively normally urging the slides to advance position, a rear stop interposed in the path of the pair of slides for limiting their retractive movement, a plunger mounted on the pair of slides and parallel with them, a spring acting on the plunger and normally urging it in the direction of the advance motion of the slides, said spring being stiffer than the spring means acting on the pair of slides, an abutment on the third slide positioned in the line of travel of the plunger and spaced therefrom a distance at least equal to the thickness of the articles to be stacked, means for feeding said articles one by one across the path of movement of the slides and in advance of their working faces, means adapted to operate intermittently on the plunger to cause the said pair of slides to retract against the resistance of the spring means acting upon them until arrested by the rear stop, and then to continue the travel of the plunger against the resistance of its spring and against the resistance of the spring means acting on the third slide until the said third slide is retracted, and then to release all the slides for travel to advance position impelled by their respective spring means.

5. In a machine for stacking razor blades and the like, a pair of connected spaced parallel slides, a third slide positioned intermediate the members of the pair, separate spring means for the pair of slides and for the third slide respectively normally urging the slides to advance position, a rear stop interposed in the path of the pair of slides for limiting their retractive movements, a forward stop also interposed in the path of the pair of slides for limiting their advance movement, a plunger mounted on the pair of slides and parallel with them, a spring acting on the plunger and normally urging it in the direction of the advance motion of the slides, said spring being stiffer than the spring means acting on the pair of slides, an abutment on the third slide positioned in the line of travel of the plunger and spaced therefrom a distance at least equal to the thickness of the articles to be stacked, means for feeding said articles one by one across the path of movement of the slides and in advance of their working faces, means adapted to operate intermittently on the plunger to cause the said pair of slides to retract against the resistance of the spring means acting upon them until arrested by the rear stop, and then

to continue the travel of the plunger against the resistance of its spring and against the resistance of the spring means acting on the third slide until the said third slide is retracted, and then to release all the slides for travel to advance position impelled by their respective spring means.

6. In a machine for stacking razor blades and the like, a pair of connected spaced parallel slides, a third slide positioned intermediate the members of the pair, separate spring means for the pair of slides and for the third slide respectively normally urging the slides to advance position, an adjustable rear stop interposed in the path of the pair of slides for limiting their retractive movements, an adjustable forward stop also interposed in the path of the pair of slides for limiting their advance movement, a plunger mounted on the pair of slides and parallel with them, a spring acting on the plunger and normally urging it in the direction of the advance motion of the slides, said spring being stiffer than the spring means acting on the pair of slides, an abutment on the third slide positioned in the line of travel of the plunger and spaced therefrom a distance at least equal to the thickness of the articles to be stacked, means for feeding said articles one by one across the path of movement of the slides and in advance of their working faces, means adapted to operate intermittently on the plunger to cause the said pair of slides to retract against the resistance of the spring means acting upon them until arrested by the rear stop, and then to continue the travel of the plunger against the resistance of its spring and against the resistance of the spring means acting on the third slide until the said third slide is retracted, and then to release all the slides for travel to advance position impelled by their respective spring means.

7. In a machine for stacking razor blades and the like, a pair of connected spaced parallel slides, a third slide positioned intermediate the members of the pair, separate spring means for the pair of slides and for the third slide respectively normally urging the slides to advance position, stops interposed in the paths of travel of the slides adapted to limit both their advance and retractive movements, a plunger mounted on the pair of slides and parallel with them, a spring acting on the plunger and normally urging it in the direction of the advance motion of the slides, said spring being stiffer than the spring means acting on the pair of slides, an abutment on the third slide positioned in the line of travel of the plunger and spaced therefrom a distance at least equal to the thickness of the articles to be stacked, means for feeding said articles one by one across the path of movement of the slides and in advance of their working faces, means adapted to operate intermittently on the plunger to cause the said pair of slides to retract against the resistance of the spring means acting upon them until arrested by the rear stop for the pair of slides, and then to continue the travel of the plunger against the resistance of its spring and against the resistance of the spring means acting on the third slide until the said third slide is retracted, and then to release all the slides for travel to advance position impelled by their respective spring means.

8. In a machine for stacking razor blades and the like, a pair of connected spaced parallel slides, a third slide positioned intermediate the members of the pair, separate spring means for

the pair of slides and for the third slide respectively normally urging the slides to advance position, adjustable stops interposed in the paths of travel of the slides adapted to limit both their advance and retractive movements, a plunger mounted on the pair of slides and parallel with them, a spring acting on the plunger and normally urging it in the direction of the advance motion of the slides, said spring being stiffer than the spring means acting on the pair of slides, an adjustable stop associated with the plunger opposing said spring, an adjustable abutment on the third slide positioned in the line of travel of the plunger and spaced therefrom a distance at least equal to the thickness of the articles to be stacked, means for feeding said articles one by one across the path of movement of the slides and in advance of their working faces, means adapted to operate intermittently on the plunger to cause the said pair of slides to retract against the resistance of the spring means acting upon them until arrested by the rear stop for the pair of slides, and then to continue the travel of the plunger against the resistance of its spring and against the resistance of the spring means acting on the third slide until the said third slide is retracted, and then to release all the slides for travel to advance position impelled by their respective spring means.

9. In a machine for stacking razor blades and the like, a pair of connected spaced parallel slides, a third slide positioned intermediate the members of the pair, separate spring means for the pair of slides and for the third slide respectively normally urging the slides to advance position, a rear stop interposed in the path of the pair of slides for limiting their retractive movement, a plunger mounted on the pair of slides and parallel with them, a spring acting on the plunger and normally urging it in the direction of the advance motion of the slides, said spring being stiffer than the spring means acting on the pair of slides, an abutment on the third slide positioned in the line of travel of the plunger and spaced therefrom a distance at least equal to the thickness of the articles to be stacked, means adapted to operate intermittently on the plunger to cause the said pair of slides to retract against the resistance of the spring means acting upon them until arrested by the rear stop, and then to continue the travel of the plunger against the resistance of its spring and against the resistance of the spring means acting on the third slide until the said third slide is retracted, and then to release all the slides for travel to advance position impelled by their respective spring means, and means for feeding said articles one by one across the path of movement of the slides and in advance of their working faces, the initial stage of the feed taking place after the pair of slides is fully retracted and continuing to completion as the third slide is retracted.

10. In a machine for stacking razor blades and the like, a pair of connected spaced parallel slides, a third slide positioned intermediate the members of the pair, separate spring means for the pair of slides and for the third slide respectively normally urging the slides to advance position, a rear stop interposed in the path of the pair of slides for limiting their retractive movement, a plunger mounted on the pair of slides and parallel with them, a spring acting on the plunger and normally urging it

in the direction of the advance motion of the slides, said spring being stiffer than the spring means acting on the pair of slides, an abutment on the third slide positioned in the line of travel of the plunger and spaced therefrom a distance at least equal to the thickness of the articles to be stacked, means adapted to operate intermittently on the plunger to cause the said pair of slides to retract against the resistance of the spring means acting upon them until arrested by the rear stop, and then to continue the travel of the plunger against the resistance of its spring and against the resistance of the spring means acting on the third slide until the said third

slide is retracted, and then to release all the slides for travel to advance position impelled by their respective spring means, and means for feeding said articles one by one across the path of movement of the slides and in advance of their working faces, the initial stage of the feed taking place after the pair of slides is fully retracted and continuing to completion as the third slide is retracted, the working faces of the slides being chamfered to permit an article to slide across them without positive obstruction.

HERMANN HILL.
